UNITED STATES PATENT OFFICE.

JOSEPH A. GRAHAM, OF HOUSTON, TEXAS, ASSIGNOR OF ONE-THIRD TO JAMES PAPADAKIS AND ONE-THIRD TO WILLIAM J. BUFORD, BOTH OF HARRIS COUNTY, TEXAS.

RAILWAY-RAIL JOINT.

Application filed October 9, 1928. Serial No. 311,360.

This invention relates to new and useful improvements in a railway rail joint.

One object of the invention is to provide a novel joint of the character described specifically designed for uniting railway rails securely together without the use of fish plates and so that the joint will not sag or shear the bolts incorporated into the joint.

Another object of the invention is to provide a joint of the character described which will be very strong and will provide a smooth tread, and which, at the same time is of simple structure so that it may be readily assembled.

A further object of the invention resides in the provision of a novel and efficient type of railway rail joint with which the rails of a track may be equipped at comparatively small expense.

With the above and other objects in view this invention has particular relation to certain novel features of construction, arrangement of parts and use an example of which is given in this specification and illustrated in the accompanying drawings wherein:

Figure 1 shows a plan view of abutting rails connected by the novel type of joint.

Figure 2 shows a side elevation thereof.

Figure 3 shows a cross sectional view taken on the line 3—3 of Figure 2.

Figure 4 shows a cross sectional view taken on the line 4—4 of Figure 2.

Figure 5 shows a cross sectional view taken on the line 5—5 of Figure 2, and

Figure 6 shows a perspective view of an end of one of the rails.

Referring now more particularly to the drawings, wherein like numerals of reference designate similar parts in each of the figures the numerals 1 and 2 designate adjacent rails of a track as a whole.

These rails are of conventional construction except as hereinafter pointed out, having the treads 3, the webs 4 and the bases 5. At one end the base 5 of the rail 2 is extended beyond the web and tread thereof forming the base extension 6 whose upper side forms a flat face 7 and upstanding from said extension, at one side of said face there is a tenon 8, coextensive in length with the base extension and integrally joined to said extension as well as to the adjacent end of the rail 2, proper. This base extension 6, is considerably thicker than the rail base 5, to give additional strength to the joint.

The adjacent end of the rail 1 has a tread extension 9 which extends beyond the corresponding end of the base 5, of said rail and whose underside has the face 10, at one side, and the depending tenon 11, at the other side, each, coextensive, in length with said tread extension and said tenon 11 being formed integrally with said tread extension and with the adjacent end of the rail 1 proper.

When assembled together the tread extension 9 abuts the opposing end of the tread of the rail 2 and the tenons 8, 11 overlap with the upper edge of the tenon 8 fitting closely against the face 10 throughout and the lower edge of the tenon 11 fitting closely against the face 7 throughout, and when so assembled the free end of each tenon abuts against the opposing vertical shoulder 12 of the other rail said shoulders 12 being formed by thickening the rail webs 4, adjacent the joint, to the full width of the rail tread 3.

The face 10, and the abutting edge of the tenon 8 are formed, one with a lengthwise groove 13 and the other with a lengthwise bead, or rib, 14 which conforms to the contour of and is adapted to fit into said groove, thus providing interlocking parts which assist in holding the overlapping tenons against spreading. The adjacent sides of said tenons are provided one with a lengthwise groove 15 and the other with a longitudinal rib 16 adapted to seat in said groove 15, when the joint is assembled. These interlocking parts assist in preventing the joint from sagging under a load as well as prevent the shearing of the securing bolts 17 which secure the overlapping tenons together. These bolts pass through registering holes 18 extending transversely through said tenons, and which are elongated, longitudinally of the tenons to permit the required longitudinal movement of the rails due to variations in temperature.

While I have shown and described what I now consider the preferred form of this invention it is obvious that mechanical changes may be made in the structure thereof and I reserve the right to make such structural changes as may be comprehended within the principle of the invention.

What I claim is:—

1. A joint for uniting adjacent ends of rails, one of said ends having a base extension and the other end having a tread extension, each extension having a tenon, said tenons overlapping and fitting together, the adj-

110

- cent sides of said tenons being provided one with a lengthwise groove and the other with a lengthwise rib fitted into said groove and means for securing said tenons together.
5. 2. A joint for uniting adjacent ends of rails, one of said ends having a base extension, formed with a face at its upper side, a tenon upstanding from said extension at one side of said face, a tread extension carried 10 by said other end having a face on its under side and a depending tenon adjacent said under face, the tenon of each of said rail ends abutting the said face of the other end, said tenons overlapping, one of said faces and 15 the abutting edge of the opposing tenon being provided one with a lengthwise groove and the other with a lengthwise rib which fits into said groove and means for securing said tenons together.
20. 3. A joint for uniting adjacent ends of rails, one of said ends having a base extension, formed with a face at its upper side, a tenon upstanding from said extension at one side of said face, a tread extension carried 25 by said other end having a face on its under side and a depending tenon adjacent said under face, the tenon of each of said rail ends abutting the said face of the other end, said tenons overlapping, one of said faces and the 30 abutting edge of the opposing tenon being provided one with a lengthwise groove and the other with a lengthwise rib which fits into said groove, means for securing said tenons together, the adjacent sides of said tenons 35 being provided, one with a lengthwise side groove and the other with a lengthwise rib which fits into said side groove.
4. A joint for uniting adjacent ends of railway rails, one of said rails having a base 40 extension whose upper side is formed with a face and an upstanding side tenon substantially coextensive in length with said extension, a tread extension carried by the other of said adjacent ends, said tread extension having an under face which fits against the upper edge of said tenon and having a depending side tenon which overlaps and fits against said upstanding tenon, the lower edge of said depending tenon fitting against said 45 face of said base extension, said under face and depending tenon being substantially coextensive in length with said tread extension, means securing the tenons together, the abutting sides of said tenons being provided one with a lengthwise groove and the other with a rib which fits into said groove, one of said faces and the abutting edge of the corresponding tenon being provided one with a 50 bead and the other with a groove which receives said bead, each of said adjacent ends having a vertical shoulder the free ends of said tenons abutting said respective shoulders, when the joint is assembled.
5. A joint for uniting adjacent ends of rails, one of said ends having a base extension and the other end having a tread extension, each extension having a tenon, said tenons overlapping and fitting together, the adjacent sides of said tenons being provided one with a recess and the other with a projection fitted into said recess and means for securing said tenons together.
- In testimony whereof I have signed my name to this specification.

JOSEPH A. GRAHAM.
